SEWING MACHINE

George A. Fleckenstein, Stratford, and Max L. Waterman, Fairfield, Conn., assignors to The Singer Manufacturing Company, Elizabeth, N. J., a corporation of New Jersey

Application June 19, 1935, Serial No. 27,300

16 Claims. (Cl. 112—241)

This invention relates to sewing machines and more particularly to high speed lock-stitch sewing machines.

An object of the invention is the provision of an improved form of balanced take-up mechanism for the needle-thread which will operate at high speeds with a minimum of vibration.

With the above and other objects in view, as will hereinafter appear, the invention comprises 10 the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings:

Figure 1 is a side elevation, partly in section, of our improved sewing machine.

Figure 2 is a top plan view with the cloth-plate and bracket-arm removed to expose the mechanism within the bed.

Figure 3 is an end elevation of the machine, with the face-plate removed.

Figure 4 is a sectional view taken substantially along the line 4—4 of Figure 1.

Figure 5 is a sectional view taken substantially along the line 5—5 of Figure 1.

Figure 6 is a rear elevation of the head of the machine showing the presser-foot lifting and tension-releasing mechanism.

Figure 7 is an end elevation of the head of the machine.

Figures 8 and 9 are sectional views taken substantially along the lines 8—8 and 9—9 of Figure 3.

Figure 10 is a bottom plan view of the throat-plate.

Figure 11 is an enlarged sectional view taken along the line 11—11 of Figure 10.

Figure 12 is a fragmentary view of one end of the feed-bar sectioned along the line 12—12 of Figure 2.

In the embodiment of the invention selected for illustration 1 is the inverted trough-shaped bed of the machine to which is secured by the screws 2' the standard 2 carrying an overhanging bracket-arm 3 which terminates in a hollow-head 4. Journaled in the spaced bearings 5 and 6 in the overhanging arm 3 is a needle-bar driving-shaft 7 having the usual balance-wheel 8 fixed thereto and journaled in the bearings 13 and 14 in the bed is a rotary hook-shaft 9 having a rotary hook 15 fixed to one end thereof and fixed to the other end is a pulley 10 which

is operatively connected to the pulley 11 by the clip-belt 12, the ratio being as 1 is to 2, and, therefore, the hook-shaft 9 makes two complete rotations for each rotation of the needle-bar shaft 7. Journaled in the bearings 16 and 17 in the bed 1 is a feed-shaft 18 having a pulley 19 fixed to one of its ends and driven by means of the clip-belt 20 from the pulley 21 carried by the shaft 7 at the ratio of 1 to 1.

Secured to the end of the feed-shaft 18 extending through the bearing 16 is a feed-lift eccentric 22 and fixed to the shaft 18 on the opposite side of the bearing is an adjustable eccentric 23. The eccentric 23 is the same as that shown in the co-pending patent application of J. H. Stearns, Serial No. 735,612, filed July 17, 1934, and which is provided with a notch 24 for the purpose of adjusting the throw of the eccentric. To effect adjustment of the eccentric, there is provided a finger-lever 25 pivoted intermediate its end to the bed 1 by means of the pivot-pin 26. One end of the lever is held against lateral movement by a boss 27 formed with an open ended guideway and is provided with a locking nose 28 which is adapted to enter the slot 24 in the eccentric. The other end extends upwardly through an opening in the bed and the lever is normally held in the position shown in Fig. 1 by means of a plunger 29 urged upwardly by a spring 30 located in a boss 31 formed on the bed of the machine. To adjust the stitch-length the operator depresses the finger-lever 25 and rotates the shaft 18 by turning the balance-wheel 8 until the desired stitch-length is obtained.

The front side of the bed 1, which is nearest the operator, is formed with upstanding bearings 32 and 32' in which is journaled a short shaft 33 having a feed-rocker 34 fixed thereto and is rocked back-and-forth by a pitman 38 having one of its ends secured to the eccentric 23 and its other end secured to a short shaft 35 carried by the feed-rocker. A feed-bar 36, carrying a feed-dog 39, bridges the space between the feed-rocker 34 and the feed-shaft 18 and has one of its ends journaled on the short shaft 35 carried by the feed-rocker and its other end overlying a block 37 which cooperates with the feed-lift eccentric 22. The feed-bar 36 is formed with a depending portion 40, and secured thereto by the screws 41 is a plate 42 which underlies the eccentric 22. From the foregoing, it will be observed that when the feed-shaft 18 rotates, the feed-bar 36 is given a feed-and-return movement by the eccentric 23, pitman 38 and feed-rocker 34, and a rising and falling movement by the eccentric 22.

55

Located at one side of the needle-bar shaft 1 and journaled in bearings 45 and 45^a carried by the wall in the overhanging bracket-arm 3 is a rock-shaft 46 formed with a boss 46' on the end extending into the hollow head 4. Secured to the boss 46' by the screw 47' is a take-up lever 47 made of light material, such as, aluminum. To the end extending into the bracket-arm there is secured an arm 48 which is operatively connected by means of the pitman 49 to the crank 50 formed on the needle-bar actuating shaft 7. Disposed on the other side of the needle-bar shaft 7 and substantially diametrically opposite the shaft 46 is a second shaft 52 journaled in the bearings 53 and 53^a. The shaft 52 is formed with a boss 52' and on the end of the shaft extending into the hollow head 4 there is secured by the screw 54' a take-up lever 54. To the other end of the shaft which extends into the overhanging bracket-arm 3 there is fixed a lever 55 which is operatively connected by a pitman 56 to the crank 57 formed on the needle-bar shaft 7.

From the above it will be observed that the take-up levers are arranged on opposite sides of their actuating shaft and substantially 180° apart and are rigidly connected to short shafts which extend through the partition or wall separating the hollow head from the overhanging bracket-arm and are actuated by mechanism located within the bracket-arm, the mechanism for each take-up lever being the same and arranged complementary to each other. This construction affords a take-up mechanism which is balanced both statically and dynamically as each action on one side of the needle-bar shaft is counteracted by an equal and opposite reaction on the other side of the shaft. It will also be observed that the ends of the take-up levers overlap. This construction permits the pivotal axes of the levers to be placed near the needle-bar shaft thereby making a more compact arrangement of the parts.

A face-plate 59 having slots therein is secured to the hollow head 4 by the screws 60 and the free ends of the take-up levers 47 and 54 are formed with laterally extending offset portions 61 and 62 which are provided with thread-eyes and extend through the arcuate slots in the face-plate 59. The face-plate carries a tension device 63, a thread-guide 64 and a flat leaf-spring 65 which acts as a thread-guide and prevents the take-up levers from throwing a loop of needle-thread in front of the needle. The thread is preferably led from the guide 66 to the tension device 63, the guide 64, the eye in the offset end of the take-up lever 47, the thread-eye in the end of the take-up lever 54, the guide 65 and thence to the needle.

As shown, the shaft 7 has secured to its end a counterbalancing disk 68 having a crank 69 attached thereto by a screw 67 and disposed with its axis offset from the axis of the shaft 7. A needle-bar 70 carrying a needle 71 extends through a suitable bearing 72 in the bottom of the head 4 and is operated by the usual pitman 73 having one of its ends pivoted to the crank-pin 69 and the other end pivotally secured to the needle-bar 70. A presser-bar 74 carrying a presser-foot 75 which cooperates with the feed-dog 39 extends through a suitable bearing 76 in the head and is spring urged downwardly by the flat-leaf spring 77 which acts against the rod 78 carried by the presser-bar 74.

Separate means are provided for raising the presser-foot and simultaneously releasing the

tension, and comprise a finger lever 79 and a treadle controlled lever 80 pivoted to the overhanging bracket-arm at 81. The lever 80 is provided with a forwardly extending arm 82 which overlies the eccentric portion of the finger lever 79 and when the finger lever is swung about its pivot 83 the cam portion engages the arm 82 and swings the lever 80 about its pivot. The lever 80 is connected to the presser-bar by means of the arm 84 which extends forwardly into the hollow head and the link 85 which has one of its ends pivoted to the arm 84 and its other end slotted to embrace a stud 86 carried by the block 87 which is clamped to the presser-bar 74 by the screws 88. To provide mechanism for concomitantly releasing the tension on the needle-thread when the presser-foot is raised, the head 4 is formed with a boss 89 which is apertured to receive a rock-shaft 90. Fixed to the end of the shaft outside of the hollow head, is a cam lever 91 (Fig. 6) and fixed to the end of the shaft within the hollow head is a cam 92 which is adapted to engage the usual releasing pin 93 carried by the tension device 63. When the presser-foot is raised, either by the finger lever or foot-treadle, the cam lever 91 is shifted, thereby rocking the shaft 90 in a clockwise direction about its axis and causing the cam 92 within the hollow head to engage the releasing pin 93 and separate the tension-disks.

Fixed to the bed 1 is a throat-plate 94 formed with the usual feed-dog slots 95 and needle aperture 96. To overcome "looping" of the needle-thread, characterized by the projection from one face of the stitched work of loose loops of needle-thread, which sometime occurs when a lock-stitch machine is operated at high-speed, there is rigidly attached to the under side of the throat-plate a cup-shaped button 97, (Fig. 11), having an upstanding wall 97' and a base 98 which is formed with an aperture 99 in vertical alignment with the needle-aperture 96 and is spaced therefrom to provide a clearance recess between and adjacent the vertically spaced apertures.

To lubricate the mechanism within the hollow head 4, the latter is formed with a depression 100 in which excess lubricant collects. Wicks 101 have one of their ends depending in the lubricant reservoir 100 and their other ends secured to the pad 102 which is carried by the plate 103 fixed to the head of the machine and the pad 102 is positioned to be engaged by the upper end of the needle-bar link 73 for the purpose of lubricating the crank-pin 69. The wick 104 has one of its ends depending in the reservoir and its other end threaded into an aperture 106 running longitudinally of the bushings 45 and 45^a and communicating with the rock-shaft 46. The wick 105, likewise conducts lubricant upwardly by capillary attraction to the aperture 108 in the bushings 53 and 53^a.

The bracket-arm 3 is formed with an interiorly arranged upstanding flange 110 and is inclined downwardly towards the head to provide an oil-reservoir 111 into which the ends of the lever 48 and pitman 49 dip thereby lubricating the take-up actuating mechanism which is located in the bracket-arm by the "splash system".

To lubricate the bearings and pivotal connections located below the cloth-plate 113, the base of the machine is inclined so as to cause excess oil to collect in a sump 114 located in rear of the bed and adjacent the pulley end of the feed-shaft 18. A wick 115 conducts lubricant from the sump 114 to the bearing 32 and a second wick 116

conducts lubricant to the bearing 32'. In both instances the wicking is threaded into a longitudinally arranged aperture in the bushings and engages the rock-shaft 33. A wick 118 is threaded through the tube 119 and has one of its ends depending in the sump 114 and its other end raised above the bed and supported by means of the tube 119 (see Fig. 9). To conduct lubricant from the wick 118 to the pivotal connection for the feed-bar the shaft 35 is formed with a longitudinally arranged groove in which is fitted a wick 117. When the feed-rocker 34 rocks back and forth the end of the wick 117 intermittently engages and wipes oil from the end of the wick 118 and conducts it to the bearing for the feed-rocker.

The wicks 120 and 121 conduct lubricant from the sump 114 to the bearings 16 and 13, respectively, and are threaded into the bearings in the same manner as the wick 115 is threaded into the bearing 32.

The wick 122 conducts lubricant to the depression 123 formed in the feed-bar 36. When the feed-bar 36 executes its four-motion movement the fibrous material in the depression wipes the oil from the wick 122 and the oil is led to the bearing block 37 and eccentric 22 through the aperture 124 and the oil conduits 125.

To lubricate the eccentric 23 a wick 127 is provided which conducts the oil to the fibrous material 128 carried by the pitman 38 an aperture being provided for conducting the oil from the fibrous pad 128 to the eccentric.

From the foregoing description considered in connection with the accompanying drawings, the construction, manner of operation and several advantages of our improved machine will be clearly and fully understood. It is apparent that such a machine has a wide variety of uses, and it will be understood that the form, construction and arrangement of the several elements employed may be varied. Therefore, the privilege is reserved of resorting to all such legitimate changes therein as may be fairly embodied within the spirit and scope of the appended claims.

Having thus set forth the nature of the invention, what we claim herein is:—

1. A take-up mechanism for sewing machines comprising a rotatable shaft, cranks carried by said shaft, a pair of rock-shafts arranged on opposite sides of and parallel to said rotatable shaft, take-up levers fixed to said rock-shafts, and mechanism for operatively connecting said cranks with said rock-shafts.

55 2. A sewing machine having in combination, a hollow overhanging bracket-arm terminating in a hollow head, a wall between said hollow head and said bracket-arm, a rotary needle-bar shaft journaled in said wall, a rock-shaft journaled in and extending through said wall, one end of said rock-shaft terminating within the hollow head and the other end within the bracket-arm, mechanism disposed within the bracket-arm and operatively connecting said needle-bar shaft with one end of the rock-shaft for operating the latter, and a take-up lever carried by the other end of the rock-shaft.

70 3. A sewing machine having in combination, an overhanging bracket-arm terminating in a hollow head and a partition between said hollow head and said bracket-arm, a needle-bar shaft journaled in said partition, a plurality of rock-shafts journaled in said partition parallel to and on opposite sides of said needle-bar shaft, take-up levers carried by said rock-shafts, and means

located within the bracket-arm and actuated by said needle-bar shaft for imparting oscillatory movements to said rock-shafts.

4. A sewing machine having in combination, a hollow overhanging bracket-arm terminating in a hollow head, a partition separating said bracket-arm from said hollow head, a needle-bar shaft journaled in said partition, a pair of rock-shafts journaled in said partition and arranged on either side of said needle-bar shaft and substantially diametrically opposite each other, take-up levers carried by said rock-shafts, and eccentric means carried by said needle-bar shaft and operatively connected with said rock-shafts for imparting oscillatory movements to the latter.

5. The combination with a sewing machine having a hollow bracket-arm terminating in a hollow head, a needle-bar shaft journaled in said bracket-arm, a needle-bar actuated thereby, a rock-shaft journaled in said bracket-arm and arranged parallel to said needle-bar shaft, a second rock-shaft journaled in said bracket-arm, said rock-shafts being arranged on opposite sides of said needle-bar shaft and disposed substantially 180° apart, take-up levers carried by said rock-shafts and cranks carried by said needle-bar shaft and operatively connected to said rock-shafts for actuating said rock-shafts about their longitudinal axes.

30 6. A sewing machine having in combination, a bracket-arm terminating in a hollow head, a needle-bar shaft journaled in said bracket-arm, a plurality of rock-shafts journaled in said hollow head and arranged parallel to the needle-bar shaft, take-up levers carried by said rock-shafts, eccentric means on said needle-bar shaft, and mechanism for connecting said rock-shafts to said eccentric means.

35 7. A sewing machine having in combination, a bracket-arm terminating in a hollow head, a needle-bar shaft formed with cranks and journaled in said bracket-arm, a plurality of rock-shafts journaled in said head and arranged parallel to the needle-bar shaft, take-up levers carried by said rock-shafts, actuating levers fixed to said rock-shafts, and pitmans connecting the cranks on said needle-bar shaft with said actuating levers.

40 8. A sewing machine having in combination, an overhanging bracket-arm terminating in a hollow head, a wall in said bracket-arm, a plurality of rock-shafts carried by said wall, a thread take-up lever carried on one end of each of said rock-shafts and mechanism within the bracket-arm for oscillating said rock-shafts about their longitudinal axes.

45 9. A sewing machine having in combination, an overhanging bracket-arm terminating in a hollow head, a wall in said bracket-arm, a pair of rock-shafts journaled in said wall, a thread take-up lever carried on one end of each of said rock-shafts, said take-up levers being oppositely directed, and mechanism within the bracket-arm for oscillating said rock-shafts about their longitudinal axes in such a manner as to cause one of said take-up levers to move upwardly and the other of said take-up levers to move downwardly.

50 10. A sewing machine having in combination, an overhanging bracket-arm terminating in a hollow head, a shaft journaled in said bracket-arm, an eccentric element carried by said shaft, a rock-shaft journaled in said bracket-arm, mechanism operatively connecting said eccentric element with said rock-shaft, all of said mech-

anism being located within said bracket-arm and a take-up element actuated by said rock-shaft.

11. A sewing machine having in combination, an overhanging bracket-arm terminating in a hollow head, a needle-bar actuating shaft journaled in said bracket-arm, eccentric elements carried by said shaft, a pair of rock-shafts journaled in said bracket-arm, mechanism operatively connecting said eccentric elements with said rock-shafts, said mechanism being located within said bracket-arm and a pair of take-up elements actuated by said rock-shafts.

12. A sewing machine having in combination, an overhanging bracket-arm terminating in a hollow head, a needle-bar actuating shaft journaled in spaced bearings carried by said bracket-arm, an eccentric element carried by said shaft and located between said bearings, a rock-shaft journaled in said bracket-arm, mechanism operatively connecting said rock-shaft and said eccentric element, said mechanism being located within said bracket-arm, and a thread take-up element actuated by said rock-shaft.

13. A sewing machine having in combination, an overhanging bracket-arm carrying a hollow head, a wall in said bracket-arm, a take-up actuating shaft journaled in and extending through said wall, thread take-up means carried by said shaft and located at one side of said wall, and mechanism within said bracket-arm and located at the other side of said wall for actuating said shaft.

14. A sewing machine having in combination,

an overhanging bracket-arm carrying a hollow head, a wall in said bracket-arm, a shaft journaled in and extending through said wall, a thread take-up lever carried on one end of said shaft and mechanism within the bracket-arm and operatively connected with the other end of said shaft for oscillating said shaft about its longitudinal axis.

15. A sewing machine having in combination a hollow bracket-arm carrying a hollow-head, a rotary needle-reciprocating shaft journaled in said bracket-arm, take-up actuating shafts journaled in said bracket-arm and disposed at opposite sides of and substantially parallel to said needle-reciprocating shaft, a take-up element carried by each of said take-up actuating shafts and mechanism within said bracket-arm for operatively connecting said needle-reciprocating shaft and said take-up actuating shafts.

16. A sewing machine having in combination a hollow bracket-arm provided with a bearing wall, a needle-bar shaft journaled in said wall, take-up actuating shafts disposed at opposite sides of and parallel to said needle-bar shaft, a take-up element carried by each of said take-up shafts at one side of said wall and mechanism operatively connecting said needle-bar shaft and said take-up shafts, said mechanism being disposed on the other side of said wall and within said bracket-arm.

GEORGE A. FLECKENSTEIN.
MAX L. WATERMAN.
